UNITED STATES PATENT OFFICE.

FRANK I. RUTLEDGE, OF PITTSBURGH, PENNSYLVANIA.

DRIER.

1,406,496.

Specification of Letters Patent. Patented Feb. 14, 1922.

Application filed May 17, 1920. Serial No. 382,086.

To all whom it may concern:

Be it known that I, FRANK I. RUTLEDGE, a citizen of the United States, residing at Pittsburgh, Allegheny County, Pennsylvania, have invented a new and useful Improvement in Driers, of which the following is a full, clear, and exact description.

The present invention relates to driers, and more particularly to driers for drying or curing food products. The invention relates in its more specific aspects to an apparatus for drying or curing short cut macaroni.

The present invention will be described more particularly with reference to its embodiment in apparatus for drying or curing short length macaroni. It is to be understood, however, that the invention may be otherwise embodied.

20 The drying of macaroni is in the nature of a curing process. To properly dry the macaroni, the macaroni should be preliminarily dried or hardened quickly for about twenty minutes to prevent souring. Care, 25 however, must be taken that the macaroni is not dried too much and spoiled.

The illustrated machine is designed to take care of one day's output of a macaroni cutting-press and to give each individual 30 drawer full of macaroni the proper curing.

In the illustrated embodiment of the invention Figure 1 is a side elevation, partially in section of the drier;

35 Figure 2 is a plan view; Figure 3 is a vertical section along the line III—III of Figure 1; and

Figure 4 is a perspective view of one of the drawers removed.

Referring to the drawings, reference number 40 2 indicates the casing of the apparatus. In one end of the casing are a plurality of vertical tiers of drawers 3.

While any convenient number of vertical tiers may be used, six vertical tiers are preferred, as they will take care of the normal output of the usual macaroni cutting-press. Each drawer holds approximately twelve pounds and each load of the cutting-press consists of about seventy-five pounds or six 50 drawers full.

The number of drawers in each tier should equal the number of operations of the macaroni cutting-press for a day's output. In the drawings sixteen drawers are shown.

55 The sixteen drawers will take care of about one cutting-press, since about twenty-five

minutes are required to run out each press of macaroni. The number of tiers of drawers and the number of drawers can, however, be varied to meet the particular conditions encountered.

60 The drier is designed particularly for curing what is known as short cut or elbow macaroni, soup pastes, noodles, etc. The drawers 3, consist of open frames with a 65 perforated bottom 4, illustrated as made of wire mesh, so that the air may pass freely through it. The drawers slide into the casings as shown in Figures 1 and 3, so that when the drawers are in place the fronts 70 of the drawers close the drawer openings in the casing.

Air passages 5 and 6, respectively, extend along the bottom and top of the casing respectively below and above the tiers of 75 macaroni-holding drawers. A fan 7 is arranged to blow air into or exhaust air from the passage 5. A similar fan 8 is arranged to blow air into or exhaust air from the passage 6. The fan 7 is placed between the 80 passage 5 and a chamber 9. The fan 8 is placed between the passage 6 and the chamber 10, which is located above the chamber 9. In the chamber 9 is a suitable heater 85 illustrated as a radiator 11. An air valve or door 12 opens from the chamber 9 to the outside air. Another valve or door 13 opens from the chamber 10 to the outside air. A third air valve or door 14 opens between the chambers 9 and 10. These three air valves 90 are connected together by rods 15 and 16 so as to operate simultaneously. When the valves 12 and 13 are open the valve 14 is shut, and when the valves 12 and 13 are shut the valve 14 is open. The valves may 95 be adjusted so that all three of them will be partly open.

The fans 7 and 8 are reversible and may be operated to cause a circulation upwardly through the macaroni-holding drawers, or 100 in the reverse direction downwardly through the drawers. Or if desired, both fans may be run to exhaust air from the drying chamber for purposes hereinafter described.

105 The operation of the apparatus in drying or curing macaroni is as follows:—

It will be assumed that the apparatus has six tiers of drawers to handle the seventy-five pound output of a single macaroni cutting-press. When the day's work is begun, 110 the top row of drawers will be filled with the elbow macaroni. The fans 7 and 8 are op-

erated to blow air upwardly through the tiers of drawers, the air being drawn in through the valve 12 and through the radiator 11, and discharged through the valve 13 at the top. It takes about twenty-five minutes for the cutting press to operate, so that after the first row of drawers has been receiving fresh air from for about twenty-five minutes, the second horizontal row of drawers is filled with the second charge from the macaroni cutting-press. The air blown upwardly through this second row of drawers absorbs moisture and therefore checks the macaroni in the first or top row from drying 15 too rapidly. The operation is continued, the circulation being maintained upwardly and the successive horizontal rows of drawers is filled, working from the top to the bottom of the drier. Each fresh drawer receives 20 fresh dry air for about twenty minutes and then its drying is checked by a drawer of fresh macaroni being slid in below it.

After the drawers are all filled and the 25 bottom drawer given its initial rapid drying, the fans are reversed for about three hours so that the circulation is downward and thereafter reversed again for about three hours to cause an upward circulation again. 30 Then the valves 12 and 13 are closed and the circulation is maintained through the valve 14 for about twelve hours. Then the valves 12 and 13 are again opened and the fans operated in each direction for an hour each. 35 The time of curing and the passing of the air valves 12, 13 and 14 will be determined by the drying but may be varied to meet the particular conditions. For example, it is often found that while the macaroni in the 40 drawers near the top and near the bottom is being cured at the proper rate, the macaroni in the middle rows of drawers will not advance rapidly enough in curing. If this occurs it may be remedied by pulling out a 45 row of drawers along the middle of the drier and operating the fans 7 and 8 both as exhaust fans, thus drawing in air at the middle of the drawers and causing a more rapid drying at this place. After the too slow drying 50 at the middle drawers is thus corrected, the drawers may be closed and the circulation continued in the regular way, one fan acting as an induced draft fan and the other as an exhaust fan. 55 While I have specifically illustrated and described the preferred embodiment of my invention, it is to be understood that the invention is not limited to such embodiment but may be otherwise embodied within the 60 scope of the following claims.

I claim:

1. A drier of the character described, comprising a drying room and means for supporting the material to be dried therein, two chambers, a reversible air circulating

means for taking the air from one of the chambers to the drying room and from the drying room to the other chamber and vice versa, air valves opening from both of the chambers to the outside atmosphere, and an air valve between said chambers, substantially as described. 70

2. A drier of the character described, comprising a casing, a plurality of tiers of perforated bottom drawers in the casing, air-circulating means comprising two reversible fans and air ducts extending from the fans to above and below the drawers respectively, substantially as described. 75

3. A drier of the character described, a casing, a plurality of tiers of perforated bottom drawers in the casing, two reversible fans arranged to cause a circulation of air through the drawers in either direction, or to cause a circulation of air in both directions from the middle of the tiers, substantially as described. 80 85

4. A drier of the character described, comprising a drying chamber and means for supporting the material to be dried therein, means for causing a circulation of air in either direction therethrough, comprising reversible blowing means and air ducts extending therefrom to opposite parts of the chamber, and means for supplying fresh air or for returning the used air or for supplying partly fresh and partly used air to either of said opposite parts of the chamber, substantially as described. 90 95

5. A drier of the character described, comprising a drying chamber and means for supporting the material to be dried therein, two reversible fans, and air ducts leading from the fans to opposite parts of the drying chamber, substantially as described. 100 105

6. A drier of the character described, comprising a drying chamber and means for supporting the material to be dried therein, and air-circulating means comprising two reversible fans and air ducts leading from the fans to opposite portions of the drying chamber, said drying chamber having provision for admitting the air to the middle of the material being dried, said fans being operable to maintain a circulation in either direction through the material or to draw air into the middle opening and from thence through the materials in each direction, substantially as described. 110 115 120

7. A drier of the character described, comprising a casing, a plurality of drawers for holding the material to be dried arranged in a tier, means for causing a circulation of air through the tier of drawers in either direction and for exhausting air from each end of the tier when an intermediate drawer is taken out to admit air into the tier, substantially as described. 125

8. A drier of the character described, 130

comprising a casing, a plurality of drawers for holding the material to be dried arranged in a tier in the casing, means for causing a drying circulation of air through the tier of drawers comprising two fans, connected by air ducts with opposite ends of said tier of drawers, means for heating the air supply

to the tier of drawers, and circulation controlling-valves for admitting the fresh air or for returning the used air to the drawers, substantially as described.

In testimony whereof, I have hereunto set my hand.

FRANK I. RUTLEDGE.
